US0D1035167S

(12) **United States Design Patent** (10) **Patent No.:** **US D1,035,167 S**
(45) **Date of Patent:** **** Jul. 9, 2024**

(54) **PET CARRIER**

(71) Applicant: **Vermont Juvenile Furniture Mfg., Inc.**, West Rutland, VT (US)

(72) Inventors: **Chris Jakubowski**, Rutland, VT (US); **Todd M. Jakubowski**, Rutland, VT (US); **Kristen Jakubowski**, Rutland, VT (US)

(73) Assignee: **Vermont Juvenile Furniture Mfg., Inc.**, West Rutland, VT (US)

(**) Term: **15 Years**

(21) Appl. No.: **29/878,873**

(22) Filed: **Jun. 28, 2023**

Related U.S. Application Data

(62) Division of application No. 29/785,128, filed on May 24, 2021, now Pat. No. Des. 996,732, which is a division of application No. 29/684,215, filed on Mar. 19, 2019, now Pat. No. Des. 923,256.

(57) **CLAIM**

The ornamental design for a pet carrier, as shown and described.

DESCRIPTION

FIG. 1 is a top, front, right perspective view of an embodiment of a pet carrier in accordance with our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom view thereof.

Broken lines represent portions of the pet carrier that form no part of the claimed design.
